(57) **CLAIM**

The ornamental design for a door banner, as shown and described.

DESCRIPTION

The present application is related to commonly assigned U.S. patent application Ser. Nos. 29/467,818 and 29/468,518 filed Sep. 24, 2013 and Oct. 1, 2013 respectively.

FIG. 1 is a front right perspective view of the door banner showing our new design;

FIG. 2 is a rear right perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof;

FIG. 8 is a bottom plan view thereof; and,

FIG. 9 is rear perspective detail view of the area 9 circumscribed within FIG. 2.

The detail depicts a flexible strap with a snap closure connecting the front to the back of the design.

The dot-dash-dot broken line circumscribing the area of the detail in FIG. 2 forms no part of the claimed design. The broken outlines of the word LOGO on the surface of the door wrap in FIGS. 1-4 form an internal boundary. All other broken lines represent environmental structure that forms no part of the claimed design.
